PLURAL FUNCTION CIRCUIT

Richard H. Stafford, Lamoni, Iowa, assignor to
 Radio Corporation of America, a corporation of
 Delaware

Application July 8, 1946, Serial No. 681,902

6 Claims. (Cl. 250—27)

1

This invention relates to plural function circuits and more particularly to an electron discharge device circuit which is readily controlled to operate either for the purpose of amplifying a radio signal or for the purpose of triggering an external circuit controlling a switching operation or the like.

In connection with signal channels of various types, it is frequently desirable to provide means for producing a switching effect. The accomplishment of this purpose has usually involved the provision of extra vacuum tubes and extra circuit elements. In accordance with the present invention, means are provided for switching the connections of an electron discharge device so that it may function either as one stage of a signal amplifying channel or as means of changing the connections of another circuit.

The invention is applicable to various types of signal channels. It is illustrated as applied to an intermediate frequency channel including a grounded grid amplifier and having the signal to be amplified injected into its cathode lead. The control grid circuit of this amplifier includes a capacitor which is short-circuited during its operation as an amplifier. When it is to be operated as a switching control tube, however, (1) the short circuit is removed from the grid capacitor, (2) its cathode is connected to ground, (3) a resistor is connected in shunt to its output circuit for starting current through it, and (4) a switch potential is applied to its control grid. These various switching operations may be effected successively by the control knob of a double pie switch or the equivalent.

The principal object of the invention is to provide an improved arrangement and method of operation whereby a stage of a signal amplifying channel may be utilized for purposes other than amplification. Additional objects are to provide simple circuit elements and switching means for connecting an electron discharge device to operate alternatively as a grounded grid amplifier or as a circuit switching element.

The invention will be better understood from the following description considered in connection with the accompanying drawing and its scope is indicated by the appended claims.

The single figure of the drawing is a wiring diagram of a preferred embodiment of the invention.

This figure shows an intermediate frequency channel including an amplifier 10, a transformer 11, an amplifier 12 and a transformer 13. Operating potential is applied from a +B terminal

5 through the tuned primary circuit 14—15 of the transformer 11 to the anode 16 of the amplifier 10, (2) through a relay operating coil 17 and the tuned primary circuit 18—19 to the anode 20 of the amplifier 12, and (3) through a resistor 21 to the shield grid 22 of the amplifier 12. Radio frequency bypass capacitors 23, 24 and 25 are shunted respectively across the shield grid circuit of the amplifier 12, the relay coil 17 and a resistor 26 connected in the cathode lead of the amplifier 12. The tuned secondary circuit 27—28 of the transformer 11 is connected in this cathode lead in series with the resistor 26.

10 During operation of the device 12 as an amplifier, a double pie switch 29 is in its right hand closed position, a signal is applied from the transformer 11 to the cathode 32 of the device 12 and the amplified signal is delivered at the tuned secondary circuit 30—31 of the transformer 13.

15 The double pie switch 29 includes a pair of blades 33 and 34 which are rotated by a single control knob as indicated by a broken line 35. When this switch is closed to the right, its blade 34 short circuits a capacitor 36 which connected 20 between ground and a grid 37 of the device 12, and this device is connected to function as a grounded grid amplifier.

25 When the switch blades 33 and 34 are rotated in a counterclockwise direction (1) the blade 34 connects the cathode 32 to ground through a lead 37 and (2) connects a resistor 38 in shunt to the output circuit of the device 12 for starting current through it. At the same time, the blade 33 connects the grid 37 through a lead 39 and a resistor 40 to a terminal 41 from which there is 30 applied a positive potential of such value as to maintain the output current of the device 12 and to produce operation of a relay 42. Further rotation of the blades 33 and 34 successively disconnects the grid 37 from the positive terminal, opens the ground connection of the cathode 32, connects the grid 37 through a resistor 43 to a negative terminal 44 so that the coil 17 is sufficiently deenergized to operate the relay 42 and 35 finally short circuits the grid capacitor 36.

40 The invention thus provides a simple and easily controlled means for adapting one stage of a signal channel to operate alternatively as an amplifier or as a device for producing a control potential which may be used for switching operations or the like.

I claim as my invention:

50 1. The combination of an alternating current amplifier including a first stage having an output circuit, a second stage including an electron dis-

charge device having a grid for controlling current conduction between its cathode and anode and having its cathode connected to ground through means coupled to said output circuit, a circuit tuned to said alternating current, a device responsive only to unidirectional current, means for applying operating potential to said anode through said tuned circuit and said device, a capacitor connected between said grid and ground, an impedance device, and a switch arranged to be closed in one position for short circuiting said capacitor and to be closed in another position for grounding said cathode and connecting said impedance means between said cathode and anode.

2. The combination of an alternating current amplifier including a first stage having an output circuit, a second stage including an electron discharge device having a grid for controlling current conduction between its cathode and anode and having its cathode connected to ground through means coupled to said output circuit, a circuit tuned to said alternating current, a device responsive only to unidirectional current, means for applying operating potential to said anode through said tuned circuit and said device, a capacitor connected between said grid and ground, an impedance device, means for applying unidirectional potential of positive polarity, and a switch arranged to be closed in one position for short circuiting said capacitor and in another position for grounding said cathode, connecting said impedance means between said cathode and anode and connecting said unidirectional potential applying means to said grid.

3. The combination of an alternating current amplifier including a first stage having an output circuit, a second stage including an electron discharge device having a grid for controlling current conduction between its cathode and anode and having its cathode connected to ground through means coupled to said output circuit, a circuit tuned to said alternating current, a device responsive only to unidirectional current, means for applying operating potential to said anode through said tuned circuit and said device, a capacitor connected between said grid and ground, an impedance device, a circuit having positive and negative terminals, and a switch arranged to be closed in a first position for short circuiting said capacitor, to be closed in a second position for grounding said cathode, connecting said impedance device between said cathode and anode and connecting said positive terminal to said grid and to be closed in a third position for connecting said negative terminal to said grid.

4. The combination of signal input means, an electron discharge device having a grid for controlling current conduction between its cathode and anode and having its cathode connected to

ground through said signal input means, a circuit tuned to said signal, a device responsive only to unidirectional current, means for applying operating potential to said anode through said tuned circuit and said device, a capacitor connected between said grid and ground, an impedance device, and a switch arranged to be closed in one position for short circuiting said capacitor and to be closed in another position for grounding said cathode and connecting said impedance device between said cathode and anode.

5. The combination of signal input means, an electron discharge device having a grid for controlling current conduction between its cathode and anode and having its cathode connected to

15 ground through said signal input means, a circuit tuned to said signal, a device responsive only to unidirectional current, means for applying operating potential to said anode through said tuned circuit and said device, a capacitor connected between said grid and ground, an impedance device, a direct current circuit, and a switch arranged to be closed in a first position for short circuiting said capacitor and to be closed in a second position for grounding said cathode, connecting said impedance device between said cathode and anode and connecting the positive terminal of said direct current circuit to said grid.

20 6. The combination of signal input means, an electron discharge device having a grid for controlling current conduction between its cathode and anode and having its cathode connected to ground through said signal input means, a circuit tuned to said signal, a device responsive only to unidirectional current, means for applying operating potential to said anode through

25 said tuned circuit and said device, a capacitor connected between said grid and ground, an impedance device, a direct current circuit, and a switch arranged to be closed in a first position for short circuiting said capacitor, to be closed in a second position for grounding said cathode, connecting said impedance device between said cathode and anode and connecting the positive terminal of said direct current circuit to said grid.

30 7. The combination of signal input means, an electron discharge device having a grid for controlling current conduction between its cathode and anode and having its cathode connected to ground through said signal input means, a circuit tuned to said signal, a device responsive only to unidirectional current, means for applying operating potential to said anode through said tuned circuit and said device, a capacitor connected between said grid and ground, an impedance device, a direct current circuit, and a switch arranged to be closed in a first position for short circuiting said capacitor, to be closed in a second position for grounding said cathode, connecting said impedance device between said cathode and anode and connecting the positive terminal of said direct current circuit to said grid, and to be closed in a third position for connecting said grid to the negative terminal of said direct current circuit.

35 8. The combination of signal input means, an electron discharge device having a grid for controlling current conduction between its cathode and anode and having its cathode connected to ground through said signal input means, a circuit tuned to said signal, a device responsive only to unidirectional current, means for applying operating potential to said anode through said tuned circuit and said device, a capacitor connected between said grid and ground, an impedance device, a direct current circuit, and a switch arranged to be closed in a first position for short circuiting said capacitor, to be closed in a second position for grounding said cathode, connecting said impedance device between said cathode and anode and connecting the positive terminal of said direct current circuit to said grid, and to be closed in a third position for connecting said grid to the negative terminal of said direct current circuit.

40 9. The combination of signal input means, an electron discharge device having a grid for controlling current conduction between its cathode and anode and having its cathode connected to ground through said signal input means, a circuit tuned to said signal, a device responsive only to unidirectional current, means for applying operating potential to said anode through said tuned circuit and said device, a capacitor connected between said grid and ground, an impedance device, a direct current circuit, and a switch arranged to be closed in a first position for short circuiting said capacitor, to be closed in a second position for grounding said cathode, connecting said impedance device between said cathode and anode and connecting the positive terminal of said direct current circuit to said grid, and to be closed in a third position for connecting said grid to the negative terminal of said direct current circuit.

45 10. The combination of signal input means, an electron discharge device having a grid for controlling current conduction between its cathode and anode and having its cathode connected to ground through said signal input means, a circuit tuned to said signal, a device responsive only to unidirectional current, means for applying operating potential to said anode through said tuned circuit and said device, a capacitor connected between said grid and ground, an impedance device, a direct current circuit, and a switch arranged to be closed in a first position for short circuiting said capacitor, to be closed in a second position for grounding said cathode, connecting said impedance device between said cathode and anode and connecting the positive terminal of said direct current circuit to said grid, and to be closed in a third position for connecting said grid to the negative terminal of said direct current circuit.
